CLAIM

The ornamental design for a faucet with a set of icons, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a faucet with a set of icons showing my new design;

FIG. 2 is a front view thereof;

FIG. 3 is a rear view thereof;

FIG. 4 is a right side view thereof; and

FIG. 5 is a left side view thereof; and,

FIG. 6 is an enlarged view showing the design of FIG. 2 with environment removed for clarity purposes.

The uneven-length broken line surrounding the shaded area represents the bounds of the claimed design and forms no part thereof. The even-length broken lines depicting the remainder of the faucet form no part of the claimed design.
